UNITED STATES PATENT OFFICE

2,252,287

SURFACE PROCESSING DEVICE

Louis Helfgott, Bronx, N. Y.

Application April 23, 1940, Serial No. 331,089

18 Claims.

This invention relates to abrading devices in general, and particularly to gang-type machines for facilitating successive abrading operations against abrading elements of different abrading qualities.

Gang grinding machines are well known in the art, but are usually employed for either shaping, sharpening or re-sharpening of tools, or for relatively rough surface-grinding of other articles. The present invention, however, has for its principal objects to provide a compactly constructed, highly efficient and readily-operable machine for fine-surfacing, in successive stages and to required degrees, of a variety of relatively small, utilitarian devices, or rather their exposed surfaces, for the purpose of rendering such articles more attractive in appearance, and for improving the wear-resistance of the exposed facets.

Another object of this invention is to provide a gang of power-driven abrading elements, having different degrees of abrading properties, and being arranged on a slant in step-like fashion and being staggered relation to one another, so that each element may be employed to its full range of effectiveness.

Still another object of this invention is to provide for each abrading element an adjustable support and guide for a work-rest or work-carrier, by means of which two instrumentalities the "work" may be brought at its pre-arranged position into operative contact with any one of the abrading elements.

A further object of this invention is to so design the work-rest or work-carrier, that the latter may be bodily placed upon and readily moved from the support and guide of one abrading element to the support and guide of any other element, without affecting the relative position of the "work" to the abrading surface of any of the elements, said work-rest having aligned, friction-reducing guide rests, adapted to straddle the guides when placed thereon, and facilitating the movement of the work-rest both in a longitudinal direction and in an arc about the longitudinal center axis of the guides.

A still further object of this invention is to so construct the work-rest or work-carrier, that the "work" held by it may not only be accurately adjusted to any required abrading position in respect to the abrading surfaces of an abrading element, but that such adjustment may be made without the cooperation of the actual abrading surface. In other words the work-rest facilitates an accurate pre-positioning and setting of the work, while removed from the abrading elements,

(Cl. 51—124)

prior to subjecting it to the abrading operation.

An additional object of my invention is to provide the work-rest with a plurality of means for facilitating either quick or gradual or fine-adjustment of the work to any desired position in respect to the abrading elements, and with means for re-positioning the work, or positioning to the same setting of successively handled work pieces of the same nature and dimensions, once the adjustment or setting for the correct abrading position of the first work piece has been determined.

The foregoing and still further objects and advantages of the present invention will become more fully apparent from the ensuing description and the accompanying drawings, in which,

Fig. 1 is a plan view of my gang abrading, lapping and polishing machine in its presently preferred form, with a swing-type work-rest in position;

Fig. 2 is a front elevation of the swing-type work-rest;

Fig. 3 is a cross-sectional view taken on line 3—3 of Fig. 2;

Fig. 4 is a side elevation of Fig. 1;

Fig. 5 is an enlarged detail view taken on line 5—5 of Fig. 2;

Fig. 6 is a compression collet employed with my work-rest;

Fig. 7 is an end view thereof;

Fig. 8 is a draw sleeve for the collet;

Fig. 9 is a longitudinal section through the collet chuck employed in my device;

Figs. 10 and 11 are, respectively, side views and end views of a work-supporting tool employed with my device;

Fig. 12 is a top view of a stationary work-rest or work-carrier;

Fig. 13 is a side view thereof;

Fig. 14 is an end view of the work-rest;

Fig. 15 is a detail view, partially in section, of a work adjusting or work position proving gauge;

Fig. 16 is a modified form of such gauge, partially in section.

Before commencing to specifically describe the construction and details of my machine, it may be well to broadly explain the principle of its operation by means of a concrete example.

It has been said in the objects that the present machine is primarily designed for handling a variety of articles which are usually provided with exposed surfaces, intended to be finished to enhance the attractiveness of an article, and to make more durable its exposed facets. Such articles may, for instance, comprise tops of salt shakers, caps for bottles, signet rings, watch

cases, and numerous other relatively small devices provided with exposed facets or surfaces.

When a large number of like articles is to be processed on my machine, it is essential that they possess the same dimensions and the same surfaces to effect an efficient and rapid handling. Taking as an example a substantially square shaped watch case, such as may be held by a work-supporting tool illustrated in Figs. 10 and 11, it will be noted that such watch case possesses sixteen facets, in addition to its front face, and that all of the facets are disposed at a certain relation to each other and to the front face. It will be also observed that the facets may be considered in four groups, and that each four facets of one group will require the same type of treatment, since their position in respect to the longitudinal center axis of the tool is the same.

In order to provide uniform treatment for each facet, it apparently becomes necessary to adjust the watch case sixteen times. By means of the present device only five major positions of the watch case need to be determined, one for the front face and one for each group of facets. When the adjustment for the facet of one group is made, the three other facets are treated by simply turning the work-supporting tool three times in a pre-determined arc about its center axis. Thus the setting of the tool for one facet of one group becomes instantaneous and automatic for the rest of the facets in that group. This saves a good deal of time and assures a high degree of precision. The aforescribed procedure also indicates that when a number of watch cases of the same type and dimensions is to be treated, my machine saves the setting of the machine for each individual case, and therefore permits continuous operation with the same character of work. The manner in which the aforesaid setting of the machine for the work to be treated is effected will become more readily understood from the following detail description of my device.

Referring to Figs. 1 and 4, there is illustrated a machine base 1, upon which is supported a standard 2, at the top of which is provided an adjustable platform 3 for accommodating motor 4. Also secured to base 1 is a mounting 5 for supporting a gang of abrading elements of different degrees of abrading properties. Mounting 5 is provided with double bearings 6, 7 and 8 for accommodating shafts 6', 7' and 8', of abrading elements 9, 10 and 11, respectively. Upon the shafts are provided pulleys 9', 10' and 11', driven by motor 4 in the direction indicated by arrow I.

The centers of the elements are disposed in a slanting plane or in a step-like relation to one another, as clearly observable from Fig. 4. In addition to their step-like position, the elements themselves are staggered relative to one another, as clearly seen from Fig. 1. In consequence of this arrangement of the abrading elements, element 9 is highest and extends furthest to the right of the operator; element 10 is somewhat lower and is disposed to the left of element 9, and element 11 is the lowest element and is disposed at the left of element 10. The half of each element, nearest to the operator, represents the effective work surface of the element, and is fully accessible to permit an unrestricted abrading function. The grade of the abrading elements will vary with the work for which they are intended.

Taking again as an example a watch case, made, for instance, wholly from precious metal, it is required that in order to effect highly polished surfaces, to first subject the facets to a relatively coarse abrading operation. Thus wheel 11, which is nearest to the operator, will have a relatively coarse grain. Element 11, and for that matter the other two elements, may either be constructed wholly from abrasive material,

10 or may be designed in the form of metal discs to which abrasive compounds of different qualities or grains, such as pumice, carborundum, rouge, etc., may be applied.

In Figs. 1 and 2 is shown a gang of but three abrasive elements, sufficient for certain purposes, such as for the "lapping" of watch cases. It is obvious, however, that for other types of work the number of elements may be increased. In the type disclosed, three stages of abrasive treatments are intended, first, a relatively rough abrasion of the future facets, preferred for articles made wholly from one material, in order to bring these facets to their correct position relative to the body of the article.

25 The next operation, performed by middle element 10, called "lapping," corresponds to a polishing operation, sufficiently rough for plated articles. The third abrading operation is performed by element 9, which is intended to provide a high polish or finish, and hardens the treated surfaces against wear.

30 Secured to machine base 1, at the right edge thereof, is a bracket 12, provided with hubs 13, in which are mounted the outer ends of combination guide and supporting rods 14, 15 and 16. These outer ends of the rods are adjustable by means of adjusting screws 17. The inner ends of the guide and supporting rods are lodged in the upright portion 18 of mounting 5. These rods serve for the accommodation, support and 40 guide, of work-rests or work-carriers, such as indicated at 19 in Figs. 1 and 4.

Description of a swing-type work-rest

45 Referring to Figs. 1, 2, 3, 4 and 5, the work-rest consists of a relatively stationary base 20, from which depend two spaced, aligned guide extensions 21 and 22, preferably equipped with aligned, friction-reducing, supporting rollers 23, by means of which the work-rest may be supported upon any one of the rods 14, 15 and 16, when bodily placed thereon. Rollers 23 are intended to straddle the rods, and are designed to facilitate the bodily movement of the work-rest, both longitudinally along the rods, and to swing in an arc about the longitudinal center axis of the rods, in the manner indicated by arrow S in Fig. 14. In this figure rollers 23 are dispensed with, V-grooves taking their place.

60 Base 20 is preferably shaped in the form of a gear segment 24, equipped with a graduation, as clearly indicated in Fig. 3. In base 20 there is provided a pivot screw 25, the vertical center line of which is disposed in the longitudinal center plane passing through the aligned rollers 23, which center plane coincides with the longitudinal center axis of the rods. Pivot screw 25 forms the fulcrum for work-rest frame 26, which is adapted to swing in an arc over the segment of base 24, and which frame is provided with an indicator 26' for the graduation of the segment, and an upright 27 for the support of tool holder 28.

At the flat portion of frame 26 there is arranged a bracket 29, in which is pivoted at 30

a double bearing 31 for a worm 32, which latter normally engages the teeth of base segment 24. Worm 32 is adapted to be operated by means of the knurled knob 33 of operating sleeve 34. A spring 35, secured to the side of frame 26 and engaging bearing 31, tends to keep worm 32 in engagement with the teeth. By swinging sleeve 34 away from frame 26, worm 32 becomes disengaged from the teeth of segment 24, and frame 26 may be swung in a horizontal plane freely to any position desired. Thereupon sleeve 34 is released so that worm 32 may again engage the teeth of the segment. Now a fine-adjustment of frame 26 relative to base 24 may be made by actuating worm 32 when knob 33 is turned.

Secured also to frame 26, a clamp 36 is provided, by means of which frame 26 may be fixed in its adjusted position. This clamp consists of a yoke, normally free from the bottom edge of base 24. Through the yoke passes a clamp screw 37, by means of which the yoke may be tightened against base 24, whereby frame 26 is prevented from moving relative to the base.

Referring now specifically to Figs. 2 and 5, standard or upright 27, forming a part of frame 26, and supporting tool holder 28, is provided with a journal head 38, in which are secured bearings 39 and 40. In these bearings is journaled shaft 41, forming a part of, and extending from the body of tool holder 28. Shaft 41 is reduced at 41' and is threaded at 42. This threaded portion is engaged by a collar 43, provided with set screw 44, for preventing the movement of the collar.

Journal head 38 has an enlargement 45', forming an abutment for a ring structure 46, held upon the head by means of a set screw 47. Ring 46 is shaped to form two parallel annuli 48 and 49. Upon the outer surface of annulus 49 there is provided a circumferential scale, as indicated in Fig. 1. Annulus 48 is adapted to be engaged by an adjustable limiting member 50, shown in Figs. 1 and 2, for defining the swinging movement of the tool holder about the axis of its journal.

To the body of the tool holder there is affixed an index or marker 51, which cooperates with the graduation provided upon annulus 49. Also secured to the body of tool holder 28 is a bracket 52 from which extends a handle 53, terminating in a ball 54. This handle facilitates the swinging of tool holder 28 in its journal when desired.

Within the tool holder body there is revolvably lodged a collet chuck 55, shown in detail in Fig. 9, consisting of a cylindrical structure with a head 55'. In rear of the head is a cone formation 56, adapted to engage a conical bearing surface 57 provided at one end of the tool holder. A similar bearing surface 58 at the other end of the tool holder accommodates the conical portion 59 of a bearing member 60. This bearing member constitutes worm gear 61 with an annular extension 62, through which latter passes a set screw 63, engaging the hollow cylindrical portion of collet chuck 55. The annular surface of extension 62 is provided with a graduation for indicating the position of the chuck in respect to the body of the tool holder. From the latter extends an indicator 63, cooperating with the scale of annulus 62. Secured in the body of the tool holder is a set screw 64 for arresting chuck 55 against movement, when in desired adjusted position.

Extending from the tool holder body is a bracket 65 in which is lodged a lever 66. The longer arm of the lever is urged in upward di-

rection by a spring 67, while its shorter arm 68 forms the bearing for a worm 69, normally forced by the spring into engagement with worm gear 61 of the collet chuck. Worm 69 may be operated by hand when knob 70 (Figs. 1, 2 and 4) is turned. When the longer lever arm is depressed, worm 69 disengages gear 61, and the chuck may be quickly turned for rough adjustment. The fine adjustment of the chuck is accomplished through the operation of gear 61 by worm 69.

Referring now to Figs. 5 to 10, inclusive, chuck 55 is provided with a guide pin 71 extending into the reduced neck portion of the chuck. A compression collet 72, illustrated in detail in Figs. 6 and 7, is provided with a longitudinal guide groove 73, adapted to accommodate pin 71 of the chuck to prevent rotation of the collet in respect to the chuck (see Fig. 5). The threaded shank 74 of the collet is engaged by the internally threaded collet draw sleeve 75, which is provided with off-set head 76, through which passes a handle 77.

Projecting from the inner smooth face of collet 72 is a guide pin 78, adapted to cooperate with a longitudinal groove 79, provided in the reduced portion 80 of work-supporting tool 81, for preventing the rotation of the tool in respect to the collet (see Figs. 5 and 10).

It will be observed from Fig. 10 that the tool is equipped with a heavier outer portion terminating in an offset 82, which latter limits the inward movement of the tool into the collet. Instead of such offset a set-ring or any other suitable arrangement may be substituted to limit the inward movement of the tool. At the end of the enlarged tool portion there is provided a work-accommodating block 83, designed for supporting a watch case of the configuration indicated in Fig. 11. This block is preferably provided with a pin 84, adapted to be received by the slot made into the watch case for accommodating the winding stem of the watch.

While work block 83, shown in the drawings, is especially intended for a watch case of a specific design, it is quite obvious that for other articles, or watch cases of other design, different work blocks will have to be provided. In practice complete tools, including work blocks, are fabricated as whole units.

Work pre-adjusting gauge

Secured to the brace or cross-member 85 of base 24, (Figs. 2, 3, 4 and 12 to 16, inclusive) and extending from the under-surface thereof, is a bracket 86, in which is rotatably mounted shank 87 (Fig. 15) or 87' (Fig. 16), at one end of which are provided means 88 for facilitating the turning of the shank, while at the opposite end is secured a gauge member or blade 89, which latter may be brought into a work-contacting position, as clearly illustrated in Figs. 13, 14 and 15. This blade may be either gradually adjusted towards or from the work by a threaded arrangement 90, lockable in position by set screw 90' (shown in Figs. 2, 3, 13 and 15), or automatically by the employment of a spring 91, illustrated in Fig. 16.

Gauge blade 89 serves for pre-adjusting the work to a position which it should correctly assume when brought in contact with the abrading surface of any one of the abrading elements 9, 10 and 11, prior to subjecting the work to the abrading operation. In other words the work may be adjusted remote from and independently of the actual abrading surface of the elements. This facilitates a more accurate setting of the

work to its proper position, and simplifies and speeds up the work-adjusting operation, which is the most essential step for correctly processing of the work.

Operation

For the purpose of proper understanding, I shall explain the operation of my device by way of an example, such as the procedure of rough surfacing, lapping, and high finishing of a watch case for which the head of the work-supporting tool, shown in Figs. 10 and 11, is designed.

Having attached the watch case to work block 83, and having inserted the work-supporting tool 81 into collet 12, and having secured the collet in chuck 55, gauge blade 89 is brought to its upward position, shown in Figs. 13, 14 and 15. The inner surface 89' of gauge blade 89 corresponds to the abrading surface of elements 9, 10 and 11. First the broad face of the watch case has to be correctly positioned. For this purpose sleeve 34 with knob 33 of worm 32 is swung away from the teeth of base 24, and frame 26 is roughly adjusted to a position at which the face of the watch case stands approximately parallel with the inner surface 89' of blade 89. A fine adjustment is then made by releasing sleeve 34 and operating worm 32. Now the position of the work is checked, and a re-adjustment is made by means of worm 32, so that the front face of the watch case squarely touches with its entire surface the surface 89' of the blade. In this position frame 26 is locked by means of clamp 36 against movement, and the gauge blade is swung downwards and out of the way, as indicated in Figs. 2 and 4.

The work-rest now is ready to be placed upon guide and supporting rod 16, serving the rough abrading element 11. By bodily swinging the work-rest in an arc about rod 16, while at the same time holding the work against the abrading surface of element 11, the first processing step of relatively rough-surfacing of the watch case front will be accomplished. Thereupon the work-rest is placed upon rod 15, without in any ways altering the position of the work. The same procedure of swinging the work-rest bodily in respect to rod 15 and holding it lightly against element 10 will produce a higher degree of surfacing of the watch case, termed "lapping." To provide a bright, very high finish for the face of the watch case, the work-rest is transferred to rod 14, and the work is held against the fine abrading surface of element 9.

Now follows the surfacing of the peripheral facets of the watch case. Screw 37 of clamp 36 is loosened, gauge blade 89 is swung again upwards and frame 26 is adjusted until one of the facets fully contacts with the inner face of blade 89. In this position frame 26 is again set by means of clamp 36.

Referring to Figs. 10 and 11, the peripheral facets of the watch case (not shown) may be imagined by observing the corresponding facets provided on work block 83. It will be found that there are four types of facets, i. e. inclined corner facets 92, inclined intermediate facets 93, small straight corner facets 94, and large intermediate side facets 95. All four types of facets in this case are disposed symmetrically to the longitudinal center axis of tool 81, which center axis passes through the center of the work block 83.

Assume that straight corner facets 94 are to be processed first. Accordingly frame 26 is first

adjusted to bring the work near gauge 89. Now arresting screw 64, holding chuck 55 against rotation within tool holder 28, is loosened so as to permit the adjustment of chuck 55. To do this, the long arm of lever 66 is depressed to disengage worm 69 from gear 61. By turning handle 71 of the draw sleeve, the chuck is also turned, and thus the work piece is roughly adjusted. Now the long arm of lever 66 is released and worm 69 is permitted to engage worm gear 61. By means of worm 69 a fine adjustment of the work position is made until facet 94 fully contacts with gauge 89.

For this position of the work, the position of the chuck is noted upon the graduation of annulus 62, by observing the number or mark indicated by pointer 63. Now set-screw 64 is again tightened to prevent the movement of the chuck, gauge 89 is released and turned downwards, and the three processing steps, previously described in connection with the surfacing of the front face of the watch case, are followed.

Since facets 94 are positioned relative to each other at distances corresponding to arcs of 90 degrees, it is a simple matter to swing chuck 55 three successive times 90 degrees from the position first indicated by index 63, and to process the three remaining facets in the manner just described, relying upon scale 62 to set the chuck.

Processing of curved surfaces

When a work piece with curved surfaces is to be processed, such as a watch case having a curved body, it becomes necessary to swing the entire tool holder within a predetermined arc to provide the finish required for the curved surfaces of such watch case. For this purpose the work is pre-adjusted similarly to the manner described above, but in addition to bodily swinging the work-carriage and sliding it upon the guide rods, the tool holder is swiveled in its journal by means of handle 53; otherwise the processing steps are identical.

Modification

For work with plain or straight surfaces, such as a watch case fitted to work block 83, the swinging operation of the tool holder is not required. In Figs. 12, 13 and 14 I have illustrated a simplified work rest, which is constructed in every respect similarly to that shown in Figs. 2, 3 and 5, with the exception of that upright 21' of frame or carriage 26' forms a one-piece structure with fixed tool-holder 28', the longitudinal center axis of which always remains parallel with the base 24. Set-screw 64', for arresting the movement of the chuck, is moved to a position just opposite to that of set-screw 64 of the formerly described work-rest.

Important feature

In both embodiments of my work-rest it will be observed that the vertical axis passing through the fulcrum point 25, provided in base 24 for frames or carriages 26 and 26', is substantially removed from the vertical center plane which passes through the longitudinal center axis of the tool-holders, as clearly indicated in Figs. 5 and 12 at X. This structural detail is of considerable importance to the practical handling of the work-rests or carriages, and the work carried by them, in respect to the abrading surfaces of elements 9, 10 and 11. It facilitates an unrestricted manipulation of the work, and prevents the cap screw, forming the pivot, from interfer-

ing with the positioning of the work in respect to the abrading surfaces of the elements.

While I have disclosed in the foregoing several specific construction and forms of the present invention, it is quite obvious that for the purpose of meeting various conditions in the processing of different work pieces, changes and improvements may be indicated, and I therefore reserve for myself the right to make such changes and improvements without departing from the broad scope of my invention, as defined in the annexed claims.

I claim:

1. In a gang abrading, lapping and polishing device, a series of driven abrading elements, work-rest guiding and supporting means for each of said elements, a work-rest bodily placed upon and adapted to be held against, and being swingable about any one of said supporting means, and being bodily movable thereupon against or away from the respective abrading elements, said work-rest having a relatively stationary, substantially horizontal base and a corresponding frame, pivotally joined with and adjustable angularly in a substantially horizontal plane relative to the base, said frame having an upright, a tool-holder supported thereby, the longitudinal center axis of the latter being disposed in a vertical plane materially distanced from the vertical center axis passing through the pivotal point of the frame, a collet chuck rotatably lodged in said tool-holder and provided with a peripheral calibration, a fixed indicator for the calibration secured to the tool-holder, a collet longitudinally movable in said chuck, guide means provided in said chuck and with said collet for preventing rotary movement of the latter relative to the chuck, a work-supporting tool longitudinally adjustable in respect to and held within said collet, guide means provided in said collet and with said tool for preventing the latter from turning in said collet, and stop means on said tool for limiting its longitudinal inward movement in respect to said collet.

2. In a gang abrading, lapping and polishing device, as set forth in claim 1, said work-rest base constituting a calibrated gear segment, said work-rest frame having an indicator cooperating with said calibration, and an operable and releasable gear segment-engaging element for accurate adjustment of the work-rest frame in respect to said base.

3. In a gang abrading, lapping and polishing device, as set forth in claim 1, said rotary collet chuck being provided with a gear for revolving the chuck, an operable and releasable gear-engaging element mounted with said tool-holder and serving for actuating and fine-adjustment of said rotary chuck, when in engagement with said gear.

4. In a gang abrading, lapping and polishing device, as set forth in claim 1, said tool-holder being journalled, substantially at right angles to its longitudinal center axis, in said upright, means for facilitating the swinging of the tool-holder in its journal, a calibration provided with a portion of said upright, and an indicator secured to the tool-holder and coacting with said calibration.

5. In a gang abrading, lapping and polishing device, as set forth in claim 1, said work-rest base constituting a calibrated gear segment having guide elements adapted to straddle said work-rest guiding and supporting means, said work-

rest frame having an operable, hingedly mounted worm, spring means normally urging said worm into engagement with the teeth of the gear segment, and means for arresting the movement of said frame at a desired, adjusted position in respect to said segment.

6. In a gang abrading, lapping and polishing device, as set forth in claim 1, said tool-holder having means for arresting said collet chuck at a desired, adjusted position within the tool-holder.

7. In a gang abrading, lapping and polishing device, as set forth in claim 1, said rotary collet chuck having an end-bearing element combined with a worm gear and an annular extension, said peripheral calibration of the collet chuck being provided upon said extension, said fixed indicator for the calibration being secured to said tool-holder.

8. In a gang abrading, lapping and polishing device, as set forth in claim 1, said rotary collet chuck having an end-bearing element combined with a worm gear and an annular extension, said peripheral calibration of the collet chuck being provided upon said extension, said fixed indicator for the calibration being secured to said tool-holder, a lever pivotally mounted with said tool-holder, a manually operable worm journalled in one arm of the lever, means for normally urging said one lever arm against said worm gear, and therefore said worm into engagement with the teeth of said worm gear, for facilitating a fine-adjustment of the collet chuck in respect to the tool-holder, the other lever arm being temporarily depressible for releasing the worm from the worm gear to facilitate quick, rough adjustment of the collet chuck.

9. In a gang abrading, lapping and polishing device, as set forth in claim 1, said tool-holder being bodily swingable in respect to said frame upright, the axis of rotation of the tool-holder being disposed substantially in a horizontal and at right angles to a vertical plane passing through the longitudinal center axis of the tool-holder, a fixed annulus forming a part of the mounting accommodating the bearings for said tool-holder, a calibration provided upon said annulus, an indicator secured to the body of the tool-holder and cooperating with said calibration,

50 another annulus extending from the mounting, and a hand-operated, adjustable instrumentality associated with said tool-holder and adapted to engage said other annulus for limiting and checking the swing movement of the tool-holder.

10. In a gang abrading, lapping and polishing devices, as set forth in claim 1, said work-rest being provided with adjustable gauge means for facilitating the adjustment of the work held by the work-supporting tool, to the abrading surfaces of said abrading elements, prior to subjecting the work to the abrading, lapping or polishing operations.

11. A machine of the character indicated, comprising a series of power-driven, staggered abrading elements, individual, relatively fixed work-rest support and guide means provided for each element, disposed substantially at right angles to the latter, and means for adjusting said support and guide means in respect to said elements.

12. The combination with a machine, as set forth in claim 11, of a work-rest placeable upon any one of said guide means and movable, bodily,

both longitudinally and in an arc about the longitudinal center axis of said guide means.

13. The combination with a machine, as set forth in claim 11, of a work-rest placeable upon any one of said guide means and movable, bodily, both longitudinally and in an arc about the longitudinal center axis of said guide means, said work-rest having a substantially horizontal base, a pair of spaced guide means-engaging instrumentalities depending from said work-rest and adapted to straddle said guide means and to always maintain the work-rest at its intended, proper relation to said guide means, and consequently to said abrading elements.

14. The combination with a machine, as set forth in claim 11, of a work-rest placeable upon any one of said guide means and movable, bodily, both longitudinally and in an arc about the longitudinal center axis of said guide means, said work-rest being composed of a substantially horizontal base, spaced and aligned friction-reducing guide means-engaging extensions depending from the base and straddling, and facilitating the movements of the work-rest upon said guide means, the vertical center plane of said aligned extensions passing through the longitudinal center axis of said guide means, a pivot provided in said base, the vertical center axis of the pivot lying in the vertical center plane of said extensions, a frame movable about said pivot and having an upright, a tool-holder supported by the latter, the longitudinal center axis of said tool-holder being substantially remote from said pivot.

15. In a machine of the character indicated, a work-rest comprising a base, a frame pivotally associated therewith, an upright forming a part of the frame, a tool-holder supported by the upright, the base having a pair of spaced, aligned, friction-reducing supports, the pivot for the frame being disposed in the vertical center plane passing through said supports, the longitudinal center axis of said tool-holder being substantially distanced from the vertical center plane of said supports, the base forming a graduated gear segment, a disengageable worm pivotally associated with said frame and adapted to normally engage the gear segment, an index provided with the frame for the graduation of the gear segment, stop means secured with the frame for fixing the adjusted position of the latter in respect to the base; a collet chuck revolvably mounted in said tool-holder and provided with a worm gear and a graduated annulus, a releasable worm pivotally secured to the tool-holder body and adapted to normally engage said worm gear, an index for the graduation of the annulus secured also to the body of the tool-holder, and means for fixing the chuck in its adjusted position in respect to the tool-holder.

16. In a machine as set forth in claim 15, fixed collet guide means within said collet chuck, a collet held by the chuck and having corresponding fixed exterior guide means, both guide means preventing the collet from rotating, but allowing its longitudinal movement in respect to the chuck, a work-holding tool in said collet, fixed interior guide means within the collet, fixed exterior guide means provided with the tool and cooperating with said interior collet guide means for preventing the rotation of the tool, but permitting its longitudinal adjustment in said collet, stop means provided with the tool for limiting its longitudinal movement into the collet, a work-supporting head at the exterior end of the tool, and means provided with said head for preventing the movement of work supported by the head.

17. In a machine of the character indicated, a work-rest consisting of a base and a frame pivoted therewith and angularly adjustable and movable horizontally thereto, an upright forming a part of the frame, a horizontal journal in the upright, a tool-holder revolvably in said journal, a pair of fixed annuli forming parts of the upright about the journal, one annulus having a graduation, a fixed index provided with the tool-holder and cooperating with said graduation, an adjustable instrumentality secured to the tool-holder and cooperating with the other annulus for controlling the swinging operation of the tool-holder in its journal, the longitudinal center axis of the tool-holder being disposed in a vertical plane which is substantially distanced from the point of pivotal connection between the base and the frame.

18. In a machine, as set forth in claim 17, a pair of spaced and aligned friction-reducing supporting extensions provided at the bottom of the base, a collet chuck revolvably mounted in said tool-holder, a collet in said chuck, a work-supporting tool in said collet, means provided with said chuck, said collet and said work-supporting tool for preventing rotary movement of the tool in respect to said chuck, the latter being provided with annular chuck-operating means and an annular, graduated member, a fixed indicator extending from the body of the tool-holder and over the graduation of said member, an adjustable and retractable gauge provided with the base, said gauge being adapted to cooperate with the work-supporting tool for pre-setting work, supported by the tool, to a proper position in respect to the abrading surface of abrasive means, to the abrading action of which the work is to be subsequently subjected.

LOUIS HELFGOTT.
